DEVICE FOR ROLLING UP CANVAS HOSE
Arthur L. Kittelson, Rte. 2, Box 491, Roseburg, Oreg.
Filed Nov. 13, 1962, Ser. No. 236,900
1 Claim. (Cl. 242—86)

This invention relates to the handling of canvas or similar collapsible hose which, when not in use, will assume substantially flat cross sectional form.

More particularly the invention is concerned with the placing of fire hose and similar cotton or canvas hoses, such as are used in the forests and parks for example, into compact coils for storage or transportation when the use of the hose is being discontinued for a period.

Since large amounts of such hose are required by fire departments, and by workers in the national and state forests where water often must be led by hose for considerable distance, it is customary to have the hose composed of sections of a hundred or more feet in length, with metal couplings at each end of each section, in order that several sections may be joined together consecutively if necessary. When extra sections of such hose are not in use, or when the use of any section is discontinued, it is customary to have each section rolled into a compact coil and tied in this position for convenient transportation by truck, or for storage purposes. Heretofore the rolling up of each section of hose into a coil, after use, after the water has been drained out of the section, and the section has assumed in flat condition, has generally been done by hand. When several sections of hose have to be rolled up in this way by hand considerable time and labor are involved. Accordingly the object of the present invention is to provide simple practical means which will eliminate a considerable portion of the time and labor required for this purpose.

A related and specific object is to provide an improved reel by which each section of such hose can be picked up, flattened and rolled into a compact roll, and then, after being tied, can be quickly discharged from the reel.

An additional object is to provide an improved reel for winding a length of hose into coil formation and to provide a guide bar attachment for such reel to position and maintain the convolutions of the coil all in the same plane during the coiling operation.

Another object of the invention is to provide an improved reel and guide bar which can be adjusted for the handling of hoses of different diameters or widths.

A still further object is to provide an improved hose winding reel with an optionally substitute hose-gripping means at the hub capable of engaging the hose at the center of the section of the hose instead of at an end of a section if it should be desired to have the coil convolutions formed of double instead of single thicknesses of hose.

The manner in which these objects are attained with the improved reel of the present invention will be readily understood from the following brief description with reference to the accompanying drawings.

In the drawings:

FIG. 1 is a front elevation of the device with a portion of the same shown in section for the sake of clarity, and with the position of a hose coil on the reel indicated in broken lines;

FIG. 2 is a side elevation taken on the line indicated at 2—2 of FIG. 1, showing the hose completely coiled and tied and ready for removal from the reel, but indicating in broken line the path along which the hose is drawn to the reel in the coiling operation;

FIG. 3 is a sectional elevation of a modified substitute attachment or hose-gripping means for coiling and supporting the hose on the reel; and

FIG. 4 is a fragmentary side elevation, drawn to a

2

larger scale, indicating how the substitute attachment of FIG. 3 is employed with the reel assembly, this figure including an end elevation of the attachment of FIG. 3, taken on the line indicated at 4—4 in FIG. 3.

5 Referring first to FIG. 1, the reel includes an open wheel 50 having a rim 10 connected by spokes 11 to a hub 12. The hub 12 is formed with a co-axial cylindrical recess 13 extending in from the outside face of the hub and the cylindrical wall of this recess is threaded.

At the opposite side from the recess 13 the hub 12 is provided with an integral co-axial extension 14, formed so as to serve as the mounting shaft for the wheel. A crank handle 15 is secured to the end of this wheel shaft 14.

15 The wheel shaft 14, and with it the wheel, are rotatably mounted in a horizontal tubular bearing 16 which is formed at the top of a vertical post 17. The bottom end of this post 17 is removably secured in a socket 18 attached to a base plate 19 which is adapted to rest on the top rim of a side wall 20 of a truck, or any other suitable convenient base support. The socket 18 is also formed with a downwardly extending pair of spaced arms 21 and 21', one of which is intended to rest against one face of the truck wall 20 or other support and the other of which carries suitable clamping means 22 for engaging the opposite face of the truck wall or other support in order to hold the socket 18, and therewith the post 17 rigidly in position.

20 The wheel shaft 14 is considerably longer than the supporting bearing 16 and a pair of collars 23 and 24 are adjustably positioned on the wheel shaft 14 adjacent opposite ends of the bearing 16 respectively, and are adjustably secured to the shaft 14 by means of suitable set screws. These collars hold the wheel shaft 14 in desired axially or longitudinally adjusted position with respect to the stationary tubular bearing 16 and thus cause the wheel to be spaced at a desired distance from the bearing 16 and post 17, the reason for which will be apparent later. Also the mounting bearing 16 is provided with a clamping screw 25 for engaging the shaft 14 in order to prevent inadvertent rotation of the shaft and wheel if desired.

25 A tubular hose-supporting member 26 has a threaded extension 27 at one end which is of the proper size to be received into the hub recess 13. This member 26 has a longitudinal slot 28 which extends from the approximate longitudinal center of the member 26 to the outer end. A hinged arm 29, having a width or diameter less than the width of the slot 28, has its inner end pivotally mounted 30 on a pin 30 extending transversely across the member 26 and intersecting the axis of the member. The length of this hinged arm 29 exceeds the distance from the pin 30 to the outer end of the member 26, and a round knob 31 is mounted on the outer end of the arm 29. Thus, as 35 apparent from FIG. 1, the arm 29 may be placed either in the vertical position, as shown in full lines in FIG. 1 (and in FIG. 2), or in the horizontal position indicated in broken lines in FIG. 1.

40 When the reel is to be used for the coiling of a section of hose, the arm 29 is set in vertical position and the coupling 32 (FIG. 2) at one end of the hose H is placed over the raised arm 29. Then, when the wheel assembly, and therewith the member 26 and arm 29, are rotated by means of the crank 15, the hose H will be wound or coiled as illustrated in FIG. 2. When the coiling of the hose section has been completed it may be tied by a cord, as indicated at 33, or the layers of the coil may be held together by any other suitable or clamping means. During the tying or fastening of the coil it will be convenient to have the reel temporarily held against rotation, and this is easily done by tightening the clamping screw 25 (FIG. 1).

To facilitate the guiding of the hose as it passes on to the reel, and to aid in keeping the convolutions of the coil exactly in the same vertical plane during the winding up of the hose section, a guide bar 34 is removably mounted on the assembly. This guide bar is shaped substantially as indicated in FIGS. 1 and 2. The guide bar has a vertical inner end portion 35 which is adapted to be inserted into a socket 36 secured on the outside of the post 17. An integral cross arm 37 on this portion of the guide bar engages the top of the socket and also bears against the side of the bearing 16 and thus holds the guide bar against rotation in its support socket. The guide bar extends obliquely upwardly and outwardly from the end portion 35, then extends substantially horizontally outwardly with a slight clearance over the top of the wheel rim 10, and finally terminates in a hose guiding portion 38 which extends downwardly in a substantially vertical plane but extends obliquely downwardly towards the direction from which the hose is being pulled onto the reel. Preferably the bottom end of this portion 38 is curved outwardly, as indicated at 38', in FIG. 1, so as to be out of the way of any possible engagement with the hose.

When the winding of the hose into the coil has been completed and the coil has been tied or otherwise secured together, the guide bar 34 is lifted out of its socket 36 and temporarily removed in order to allow the coil of hose to be slid off from the reel assembly. The coil is then slid outwardly off the hose-supporting member 26, the hinged arm 29 swinging outwardly into horizontal position as the coil is moved outwardly with respect to the member 26. Should the arm 29 have become tightly engaged by the inner socket 32 of the hose coil, a slight partial rotation of the wheel and shaft in reverse direction will be sufficient to free the arm 29 and enable it to drop down to horizontal position freely as the coil is pulled outwardly.

The fact that the position of the wheel shaft 14 can be adjusted in an axial direction with respect to the stationary bearing 16, and thus with respect to the guide bar 34 enables the reel to accommodate hoses of different width or diameter. Thus, referring to FIG. 1, if a wider hose than that indicated at H is required to be wound, the shifting of the shaft 14 and therewith the shifting of the wheel and hose-supporting member 26, to the right as viewed in FIG. 1, with respect to the stationary bearing 16, post 17 and guide bar socket 36, will result in a larger spacing between the wheel and the outer portion 38 of the guide bar and thus enable a wider hose to be accommodated in this space. Such shifting of the shaft 14 is easily accomplished by adjusting the collars 23 and 24.

In some instances and under some conditions if may be desired to start at the approximate center of a hose section for forming the hose into the desired coil instead of starting at an end of the section. To enable this to be accomplished by the reel assembly I provide a substitute hose-supporting and gripping member 39 shown

in FIG. 3. This substitute member comprises a main partially tubular portion 40, open at the outer end, having a slot 41 extending longitudinally the entire length, and having an integral threaded extension 42 on the inner end of exactly the same size as the inner threaded extension 27 on the member 26 (FIG. 1). When this substitute hose-supporting member 39 is to be used the member 26 is removed by being unscrewed from the hub recess 13 and the member 39 is mounted in its place.

The manner in which the center portion of the hose section H' is then held by this substitute member 39 is illustrated in FIG. 4. The slot 41 of the member 39 enables a transverse fold of the hose to be inserted in the slot, whereupon the turning of the reel causes the hose to be wound into a coil having convolutions formed of double thicknesses instead of a single thickness of the hose. The coil of hose is then easily slid off from the member 39. The transverse hose fold at the center ordinarily will readily slide out from the holding slot 41 during the removal of the coil, but should the fold have become tightly clamped in the slot 41 a slight reverse rotation of the wheel and therewith of the member 39 will be sufficient to free the transverse fold so as to allow the inner portion of the coiled hose to be slid off easily from the member 39.

I claim:

In a device of the character described for forming collapsed hose into a roll, a wheel, a wheel shaft, said wheel secured to one end of said shaft, a crank handle at the other end of said shaft for rotating said shaft and wheel, a bearing mounting for said shaft, a rigid support for said bearing mounting, and a hose-supporting member secured in the hub of said wheel and extending from said hub and wheel oppositely from said shaft and co-axial with said hub and shaft, said hose-supporting member provided with a longitudinal slot extending longitudinally along said member and through the outer end of said member, a hose-engaging arm having one end hingedly mounted in said slot, said arm extending beyond the end of said member when positioned co-axially in said slot but adapted to be swung into a position substantially normal to the axis of said member for temporarily engaging an end of the hose when the hose is being rolled-up on said member, whereby said arm will be swung towards co-axial position in said slot when the rolled-up hose is manually slid off from said member, thereby releasing the hose end.
